UNITED STATES PATENT OFFICE.

LOUIS B. RASMUSSEN, OF DULUTH, MINNESOTA.

TOBACCO-CAN.

1,202,100.

Specification of Letters Patent. Patented Oct. 24, 1916.

Application filed April 1, 1916. Serial No. 88,237.

To all whom it may concern:

Be it known that I, LOUIS B. RASMUSSEN, a citizen of the United States, residing at Duluth, in the county of St. Louis and State of Minnesota, have invented certain new and useful Improvements in Tobacco-Cans, of which the following is a specification, reference being had therein to the accompanying drawing.

This invention consists of certain improvements in receptacles and relates particularly to such used as tobacco cans, and the object is to provide a simple construction of can whereby the contents thereof, whether much or little, may be maintained near the open or discharging end of the can for convenient accessibility. I am aware that several devices of this character having the same objects in view have been patented, as for instance, a telescopically collapsible box, U. S. Patent 1119467, composed of two substantially equal parts vertically, one telescoping within the other, but each half being equally susceptible to influence from an outside source, makes the maintained relative position thereof unreliable, the external shape of irregular form, and the benefits derived affecting only half the contents of the box. Other patents, such as Nos. 1148947 and 1089889, disclose vertically movable false or auxiliary bottoms, either fixed to or operating in conjunction with the paper cartons within the cans or packages, and in the former, the carton, false bottom and contents of the can are raised and lowered each time access is had thereto, while in the latter the false bottom is raised by the carton and remains each time to the position adjusted, the access carton being torn away and the false bottom not depressible except by adjusting the shape of the can.

My present invention is to overcome the apparent disadvantages of the various constructions referred to and at the same time provide additional advantages both in simplicity of construction and usefulness.

The accompanying drawing forming part of this application and in which like reference characters indicate like parts, represents a perspective view of a portion of one of my improved cans, partly in cross section.

1 represents the body portion of the can equipped with the usual hinged cover 2, and of a form common to the trade, except that the usual bottom found therein is omitted. The lowermost edge 3 of the body portion 1

is turned in and upwardly forming an internal flange 4 preferably spaced a distance from the adjacent wall of the body portion. A bottom 5 is fitted within the body 1 and is made to snugly fit therein though readily adjustable longitudinally in relation to the can. This bottom is preferably of substantially horizontal I-shape in cross section, comprising the bottom member 5 proper, and the side members 6, the latter projecting both above and below the former and forming flanges thereabout, the depending portion 7 of which is designed to become engaged within the groove formed within the lowermost edge of the body 1 by the inwardly upturned flange 4. For obvious reasons, this is to provide as tight and secure a union as possible between the bottom and the body portion of the can when the latter is full and being stored or shipped prior to being in the hands of the consumer.

The vertical portion 7 of the movable bottom 5 is just sufficiently long to suitably guide the bottom when being moved and prevent its tipping or binding unduly against the walls of the body 1 and the upwardly extending portion thereof receives the bottom of the carton 8 in which the tobacco is contained. Thus when the tobacco is used from the can, the bottom 5 may be forced upwardly which will elevate the carton and its contents to the desired position and the former may be torn away to make more accessible the latter. If occasion should arise for refilling the can after a portion has been used therefrom, or adding more tobacco to that remaining therein, all that is necessary is to force the bottom and contents down by slight pressure upon the latter.

From the foregoing it is evident that I have provided a novel and simple construction of can having a conveniently reciprocal bottom which when in its extreme outermost position, engages and reinforces the lower edges of the can and forms a substantially tight joint therewith.

Having thus described my invention what I claim as new and desire to secure by Letters Patent is:

The combination with a tobacco can of the character described having an open ended body portion and a hinged cover upon the upper end thereof, of an upwardly turned flange about the lower end forming a continuous groove around the inner wall

of the bottom and a slidably movable bottom having a vertically straight continuous encircling flange projecting both above and below the bottom, whereby the downwardly projecting portion of the flange will rest within the groove when the can is full, substantially as and for the purpose described.

In testimony whereof I hereunto affix my signature in the presence of two witnesses.

LOUIS B. RASMUSEN.
